UNITED STATES PATENT OFFICE.

OTIS B. KENT, OF WASHINGTON, DISTRICT OF COLUMBIA, AND ROBERT L. MILLER, OF SPOKANE, WASHINGTON, SAID MILLER ASSIGNEE TO OTIS AUTOMATIC TRAIN CONTROL, INC., OF SPOKANE, WASHINGTON, A CORPORATION OF WASHINGTON.

TRACK MECHANISM FOR AUTOMATIC TRAIN-CONTROL SYSTEMS.

Application filed June 30, 1921. Serial No. 479,056.

To all whom it may concern:

Be it known that we, OTIS B. KENT and ROBERT L. MILLER, citizens of the United States, and residents of Washington, in the 5 District of Columbia, and Spokane, in the county of Spokane and State of Washington, respectively, have invented certain new and useful Improvements in Track Mechanism for Automatic Train-Control Systems, of 10 which the following is a specification.

Our invention relates to improvements in track mechanisms for automatic train control systems, and it consists more particularly in the provision of a ramp device 15 which is capable of movement into or out of the path of travel of a shoe constituting a part of the train carried mechanism whereby under predetermined conditions said shoe is actuated in a manner to cause 20 the train carried mechanism to act on the air brakes of the train to thereby control the travel of the latter.

An important purpose of our invention resides in the provision of a ramp device 25 of the character mentioned which is of simple and inexpensive construction, possessing few parts compactly arranged, and unlikely to get out of order, which is gravity operated in a positive manner to a normally 30 active shoe actuating position and which may be electrically or otherwise operated to inactive position.

Our invention consists essentially in the provision of a supporting element for one 35 or preferably two pivoted ramp rails, a projectable and retractible shoe operable to swing said rails on their pivots to dispose them either in active or inactive position with respect to the train carried mechanism 40 designed to be actuated thereby and means for effecting desired movements of said shoe; said means including a pair of links forming a toggle between the casing and shoe, a lever pivoted to the shoe and to the 45 casing, and a rod connecting said lever with the toggle. With such an arrangement we accomplish the desired purposes of quickly and easily moving the shoe and consequently the ramp rails either to active or inactive 50 position and of locking the toggle against collapse under the influence of downward

pressure on the shoe when the same is in projected position.

Other purposes as well as the nature and advantages of our improvements will be apparent to those skilled in the art to which our invention appertains when the accompanying drawings are considered in the light of the detailed description thereof to follow. It is desired to point out and have it understood, however, that various changes and desirable additions may be made in and to the structure illustrated without departing from the spirit or scope of our invention as defined in the appended claims.

In the drawings wherein like characters of reference denote corresponding parts in the different views:—

Fig. 1 is a longitudinal section through a ramp device embodying the novel characteristics of our invention showing the shoe actuating elements in normal position; and

Fig. 2 is a view similar to Fig. 1 showing the shoe actuating elements moved to non-active position.

Referring now to the drawings in detail, 10 designates a somewhat elongated, preferably rectangular hollow casing which serves as a housing and support for the movable elements of our device and which is adapted to be secured in any suitable manner at a desired location along the tracks of a railroad whereby said movable elements are disposed in position to actuate a train carried shoe 11 which is connected in any preferred manner to mechanism whereby actuation of said shoe will, under predetermined conditions act through said mechanism to control the travel of the train. The specific type of mechanism to be actuated by our improved ramp device constitutes no part of our present invention and we have therefore illustrated only the shoe element of one form of such mechanism in order to show the relation between our device and that part of a train carried mechanism which it is designed to actuate.

With more particular reference to the drawings it will be observed that the upper wall of the casing 10 has pivoted thereto at an approximately intermediate point thereon one end of a ramp rail 12. This

ramp rail is thicker near its pivoted end than at its free end and is tapered towards said free end where it terminates in a relatively thin edge.

5 A second ramp rail 13, in all respects a duplicate of the ramp rail 12, is also pivoted to the upper wall of the casing near one end of the latter, and as shown, the free end of this rail extends towards the 10 free end of rail 12. Both rails are adapted to swing in a vertical plane and their free ends are designed to be at all times supported upon a shoe 14 which is located midway between the pivots of said rails and 15 which is adapted to be projected and retracted in a vertical direction with respect to the casing 10 whereby said ramp rails may be swung to a raised position as illustrated in Fig. 1 or permitted to move downward to a lowered position as shown in 20 Fig. 2.

The means for projecting and retracting the shoe 14 consists primarily of a lever 15 disposed within the casing and pivoted at 25 an intermediate point thereto as at 16. One end of this lever is pivoted as at 17 to an under portion of the shoe and its other end is weighted as at 18, said weighted end acting to raise the other end and thereby normally hold the shoe in a projected position and the ramp rails disposed at an upward inclined from their respective pivoted ends toward the shoe.

In addition to the lever 15 other means 35 has been provided to assist in projecting and retracting the shoe and to support and hold the same substantially rigid, particularly in its projected position. This means consists of a pair of links 19 and 20, the 40 former of which is pivoted as at 21 to an under portion of the shoe while the latter is pivoted as at 22 to the casing, or more desirably, to a block such as shown at 23 secured to the lower wall of the casing. 45 Said links 19 and 20 are relatively pivotally connected at their adjacent ends so that a break joint 24 is provided and connecting this break joint with one end of a short lever 25, which is pivoted to the casing at 50 its other end as at 26, is a rod 27. Carried by the lever 15 is a pin 28 which rides in a slot in the short lever 25 and which acts to swing said short lever to move the rod 27 to either break or straighten the 55 toggle produced by said links 19 and 20 when the weighted end of lever 15 is raised or lowered as the case may be. From the foregoing it is obvious that as long as the weighted end of the lever 15 is in its lower- 60 most position the joint 24 is locked by the rod 27 and no downward movement of the shoe can occur. This is the normal position of the parts mentioned, the same being maintained in the relation shown in Fig. 1 65 by the weight 18 as is apparent. Preferably

the weight 18 is formed as the magnet bar of an electro-magnet 29 fixed within the casing in any suitable manner and upon energization of which the magnet bar is moved to the position shown in Fig. 2, 70 whereupon the joint 24 is broken and the shoe moved to a lowered position, thereby permitting the rails 12 and 13 to swing downward and assume an inactive position.

The magnet 29 is designed to be energized through a relay system of any well known or preferred type and under predetermined conditions the ramp rails may assume either of the positions illustrated in the drawings. When in the position shown in Fig. 1 the shoe 11 carried by a train passing over the device will engage one or the other of the ramp rails, depending upon the direction of approach of the train, and will be raised thereby, thus actuating the train mechanism and brakes. On the other hand when in the position shown in Fig. 2 the shoe 11 will pass freely over said ramp rails and the train mechanism and brakes 80 will be unaffected. 90

The shoe 14 is desirably so shaped upon its upper face as to provide seats to receive the free ends of the ramp rails and at the same time provide an even continuation of their upper faces. Desirably too the ramp rails are pivoted on rods extending between pairs of lugs rising from the upper face of the casing and their pivoted ends are rounded so as to have a bearing on the casing and relieve the pivot rods of a portion of their weight. Furthermore, we deem it within the spirit of our invention to make use of a solenoid arrangement in lieu of the electro-magnetic arrangement herein illustrated and to make various other changes and additions as may from time to time become desirable within the scope of our invention as defined in the appended claims. 100

We claim:

1. A ramp device for automatic train control apparatus including a pair of ramp rails arranged in end to end relation, a weight operated member normally exerting an upward force upon the adjacent inner ends of said ramp rails to maintain them normally projected, and electro-magnetic means to retract said member thereby to permit retraction of said ramp rails under the influence of gravity. 110

2. A ramp device for automatic train control apparatus comprising a casing, a pair of ramp rails carried by said casing and arranged in end to end relation, a member within said casing pivoted intermediately and having one end weighted whereby its other end is maintained normally elevated, an operative connection between the normally elevated end of said member and the adjacent ends of said ramp rails whereby the latter are maintained normally projected, 115 120 125 130

and electro-magnetic means for retracting the normally elevated end of said member whereby said ramp rails may be depressed by gravity.

- 5 3. A ramp device for automatic train control mechanism comprising a supporting element, a ramp rail pivoted thereto for swinging movement, a shoe engageable with said rail for swinging the same, a pair of relatively pivoted links between the shoe and said supporting element, a lever for actuating said shoe, and a connection between said lever and said pivoted links whereby the latter are held against collapse under the influence of pressure against said shoe.
- 10 4. A ramp device for automatic train control mechanisms comprising a supporting

casing, a ramp rail pivoted to said casing for swinging movement, a shoe projectable and retractable with respect to said casing 20 and engageable with said rail for swinging the same, a lever pivoted to the casing and to said shoe for moving the latter, a pair of relatively pivotally connected links connecting the casing and shoe, a rod connecting said links with said lever, a weight in the form of a magnet bar carried at the free end of said lever, and an electro-magnet disposed in operative relation with said weight.

In testimony whereof we hereunto affix 30 our signatures.

OTIS B. KENT.
ROBERT L. MILLER.
